DESIGN FOR A MULTIPLE ENVELOPE OR SIMILAR PACKAGE

Leroy L. Salfisberg, South Orange, N. J., assignor
to Ivers-Lee Company, Newark, N. J., a corpora-
tion of Delaware

Application September 20, 1938, Serial No. 80,001

Term of patent 14 years

To all whom it may concern:

Be it known that I, Leroy L. Salfisberg, a citizen
of the United States and a resident of South
Orange, in the county of Essex and State of New
Jersey, have invented a new, original, and ornamental
Design for a Multiple Envelope or Similar
Package, of which the following is a specification,
reference being had to the accompanying drawing,
forming part thereof.

Figure 1 is a front elevational view of a multiple
envelope or similar package showing my new de-
sign.

Figure 2 is an elevational view of the right hand
edge of the multiple envelope or similar package
shown in Figure 1.

Figure 3 is a similar view of the left-hand edge.

Figure 4 is a top edge view of the multiple en-
velope or similar package shown in Figure 1.

Figure 5 is a fragmentary plan view on an en-
larged scale of a portion of the multiple envelope
or similar package along the line 5—5 of Figure 1,
and

Figure 6 is a fragmentary top elevational view
of the portion of the multiple envelope or simi-
lar package shown in Figure 5.

The design is characterized by a multiple en-
velope of the configuration shown, provided with
compartments formed in certain predetermined
relationship, said compartments being defined by
border corrugations disposed in the manner
shown.

I claim:

The ornamental design for a multiple envelope
or similar package, as shown and described.

LEROY L. SALFISBERG.
